(57) **CLAIM**

The ornamental design for a hood for a work vehicle, as shown and described.

DESCRIPTION

FIG. 1 is a perspective view of a hood for a work vehicle according to an exemplary embodiment of the present subject matter.

FIG. 2 is a front view of the hood illustrated in FIG. 1.

FIG. 3 is a rear view of the hood illustrated in FIG. 1.

FIG. 4 is a first side view of the hood illustrated in FIG. 1. FIG. 5 is a second side view of the hood illustrated in FIG. 1.

FIG. 6 is a top view of the hood illustrated in FIG. 1; and, FIG. 7 is a bottom view of the hood illustrated in FIG. 1. The broken lines contained within the figures, including, but, not limited to, any dash-dot broken lines and/or dash-dash broken lines, represent portions of the hood for a work vehicle that form no part of the claimed design. Additionally, contour lines and/or surface shading are illustrated simply for purposes of highlighting the solid-rendering, and, thus, form no part of the claimed design.

The present design is not limited to the exact details shown in the drawings, since equivalents and colorable imitations thereof will be evident to a person of ordinary skill in the art. Within the scope of the appended claim, in which we intend to cover only the ornamental and novel elements shown in the drawings, the present design may be practiced otherwise than as specifically shown and described herein.

Any combination of the illustrated features, including claimed features and unclaimed features, may be claimed in this application or a continuing application claiming priority to this application by converting any portion of the broken lines to solid lines, any portion of the solid lines to broken lines, or both.

1 Claim, 7 Drawing Sheets
